UNITED STATES PATENT OFFICE

127,528

DESIGN FOR A SHOE HEEL

Anthony Terpak, Pittsfield, Mass., assignor to
General Electric Company, a corporation of
New York

Application September 24, 1940, Serial No. 95,331

Term of patent 14 years

To all whom it may concern:

Be it known that I, Anthony Terpak, a citizen of the United States, residing at Pittsfield, in the county of Berkshire and Commonwealth of Massachusetts, have invented a new, original, and ornamental Design for a Shoe Heel, of which the following is a specification, reference being had to the accompanying drawing, forming a part thereof.

In said drawing:

Fig. 1 is a perspective view of a shoe heel showing my new design.

Fig. 2 is a side view.

Fig. 3 is a rear view.

The characteristic features of my design reside in a translucent heel having a series of vertical holes of varying depth interrupted by a plurality of larger wedge-shaped holes, and having a fluted portion surrounding the base of the heel, as shown.

I claim:

The ornamental design for a shoe heel, as shown and described.

ANTHONY TERPAK.
